UNITED STATES PATENT OFFICE

111,571

DESIGN FOR A WHAT-NOT

Joseph A. Rankel, Oshkosh, Wis.

Application August 15, 1938, Serial No. 79,360

Term of patent 7 years

To all whom it may concern:

Be it known that I, Joseph A. Rankel, of Oshkosh, in the county of Winnebago and State of Wisconsin, have invented a new, original, and ornamental Design for a What-Not, of which the following is a specification, reference being had to the accompanying drawing, forming part thereof.

In the drawing:

I claim:

The ornamental design for a what-not, as shown.

JOSEPH A. RANKEL.
